BRASSIÈRE AND SIMILAR GARMENTS

Jack Glick, Bronx, N. Y., assignor to The Gluckin Corporation, New York, N. Y., a corporation of New York

Application February 14, 1945, Serial No. 577,861.

5 Claims. (Cl. 2—42)

1

This invention relates to brassières of the type and kind dispensing with the use of conventional shoulder straps. More particularly, the invention deals with brassières of the kind defined wherein the cups or pockets includes circumferential channels or passages extending from the bottom of the cups or pockets to inner and outer sides of the pockets, and to the inclusion of brace or supporting members in said channels or passages in the form of what might be termed open rings, with means providing detachable mounting of the brace or supporting members with respect to the pockets. Still more particularly, the invention deals with garments of the class described including supplemental supporting straps or bands extending from upper outer side portions of the pockets to the central portion of the back band of the brassière and adjustable with respect to the back band of an opposed pocket in aiding in the support of the brassière upon the body of the wearer. The novel features of the invention will be best understood from the following description when taken together with the accompanying drawing, in which certain embodiments of the invention are disclosed, and in which the separate parts are designated by suitable reference characters in each of the views, and in which:

Fig. 1 is a front and slightly perspective view of a brassière made according to my invention, with part of the construction broken away.

Fig. 2 is a rear view of the back band of the brassière on an enlarged scale.

Fig. 3 is a view similar to Fig. 2, showing the parts detached.

Fig. 4 is a section on the line 4—4 of Fig. 1 on an enlarged scale.

Fig. 5 is a partial section on the line 5—5 of Fig. 1 on an enlarged scale; and

Fig. 6 is a diagrammatic view showing the rear portion of a modified form of side and back band.

In Fig. 1 of the drawing is shown a brassière formed from two substantially similar pockets 10 and 10a. In the construction shown, these pockets are formed from inner and outer facings, for example, the inner facing 11 and the outer facing 12 of the pocket 10, note Fig. 4, and the inner facing 13 and outer facing 14 of the pocket 10a, note Fig. 1. Both of these facings will be shaped to give the desired bust contour to the pockets, for example, by the formation of darts therein, as indicated by the dart 15 on the pocket 10 and the dart 16 on the pocket 10a. The pockets 10 and 10a are formed with relatively wide inner edges 17 and corresponding outer edges 18. The inner edges are joined by a strap 19, which may be elastic.

Attached to the outer edges 18 of the pockets 10 and 10a are side and back bands 20 and 21. These bands terminate in coupling tabs 22 and 23 respectively, which join the ends of the bands 20 and 21, preferably in elastic straps 24 and 25, note in this connection Figs. 2 and 3 of the drawing. Secured to the outer surface of the tab 23 are two hooks 26, of a conventional hook and eye, and secured to the inner surface of the tab 22 are two pairs of bars 27 for engagement with the hooks 26 in adjusting the band for size upon the body of a wearer.

Also secured to outer surfaces of the tab 22 is a pair of bars 28, and a corresponding pair of bars 29 is secured to the outer face of the tab 23. Extending from the upper corner portion of the outer edges 18 of the pockets 10 and 10a, as seen at 30, note Fig. 1, are supplemental supporting straps 31 and 32. Arranged in these straps intermediate the ends thereof and at any desired position thereon, are elastic straps 33 and 34. In the construction shown, the straps 33 and 34 are disposed near the ends of the straps 31 and 32.

Secured to the ends of the straps 31 and 32 are hooks 35 and 36, note Figs. 2 and 3 of the drawing. After the tabs 22 and 23 have been properly coupled together by engagement of the hooks 26 with two of the bars 27, the straps 31 and 32 are then drawn tightly above the bands 20 and 21 and crossed at the back of the band and coupled thereto by engaging hooks 35 and 36 with one of the bars 29 and 28. It will be understood that one strap is secured in position first and then the other strap is passed over the first strap and secured in position. The two bars 28 and 29 provide adjustability for controlling the support of the brassière upon the body of the wearer.

It will be apparent that the strap extending from one pocket is attached to the band which extends from the opposed pocket, and preferably at the lower edge portion of said band. This exerts a pull upon the lower part of the side and back bands, which also aids in supporting a brassière of the type and kind in position without the use of conventional shoulder straps. In this connection, it will be understood that while the garment is designed primarily to be what might be termed strapless, in some instances, shoulder straps can be employed, but if employed, the straps would extend from the upper outer corner portions of the pocket at the points 30 and not from the upper central portions of the pockets.

Each pocket 10 and 10a, or the inner mounting facing sheets thereof are stitched together by 55 parallel stitchings as indicated at 37 on the pocket

10, and 38 on the pocket 10a, in the curved paths which are diagrammatically illustrated in Figs. 1 and 2 of the drawing, to stop stitchings 39 and 40, at the upper portion of the pocket 10, and 41 and 42 at the upper portion of the pocket 10a. The stop stitchings 39—40 and 41—42 transverse the stitchings 37 and 38 and define the ends of channels or passages 43 and 44 of the pockets 10 and 10a, in which brace or supporting members 45 and 46 are arranged.

The formation of the channels or passages 43 and 44, as well as the members 45 and 46 is such as to provide supports which are arranged at the lower and both inner and outer sides of the pockets, the supports extending to points above the inner and outer side edges 17 and 18 of the pockets. The members 45 and 46 of the supports may be said to be in the form of open rings or to be substantially horseshoe shaped in form, as viewed in plan.

The members 45 and 46 can be composed of any suitable reinforcing material having a greater degree of stiffness or rigidity than the fabric from which the pocket is formed, and in some instances, may be composed of metal or plastic materials, preferably of such construction as to facilitate formation of the curved contour in cross section, as seen in Fig. 4 of the drawing, for these members fit upon the peripheral portions of the breasts and body of the wearer. In other words, these members should preferably have a slight transverse flexibility as well as a longitudinal flexibility. In forming the members from plastic and similar materials, they may be pre-formed to the desired cross sectional curvature, as diagrammatically illustrated in Fig. 4.

In using supporting members 45 and 46 of metallic, plastic or similar materials, it is desirable to remove these members from the pockets in laundering the garment. For this purpose, one of the facings of each pocket adjacent one of the ends 39—42 is provided with a buttonhole or similar opening, as indicated for example, at 47 in Fig. 5 of the drawing, the buttonhole being shown inwardly of but adjacent the stop stitch 39 and on the inner facing 11 of the pocket. It will be understood that the companion pocket 10a will have a similar opening formed adjacent the stop stitch 42, as is indicated in dotted lines at 48 in Fig. 1 of the drawing. The openings 47 and 48 will be formed sufficiently close to one end of the members 45 and 46 to facilitate detachment of the end through the opening by flexure of the material, and yet a pocket will be formed adjacent the stops 39 and 42 to retain the members 45 and 46 against accidental displacement.

In Fig. 6 of the drawing is shown a slight modification of the structure illustrated in Figs. 1 to 5 inclusive wherein the side and back bands are composed of inner and outer facings and the supplemental straps are disposed, for the major part, between these facings. In Fig. 6, 49 represents the rear end portion of a side or back band equivalent to the band 20, the tab end being diagrammatically illustrated at 50, this tab being the same as the tab 22. At 51 is shown the elastic strap similar to the strap 24, and at 52 is a strap similar to the strap 31. The side and back band 49 will be composed of inner and outer facing sheets 53 and 54 respectively, thus the strap 52 in extending from the upper outer side of a pocket can for the most part be arranged between the facings 53 and 54 and extend out through a buttonhole 55 formed in the outer facing 54 near the elastic strap 51. All detailed structures with respect to

the tab 50 are omitted for sake of simplicity, and in this respect the illustration in Fig. 6 is diagrammatic simply to show the method of mounting the strap 52. This same structure will be applicable to the side and back band at the other side of the garment and equivalent to the band 21.

By extending the supporting members 45 and 46 to the upper portions of inner and outer sides of the breast pockets, it will appear that the 10 breasts will be disposed within braces which envelope all but the upper portions of the breasts, thus providing all the support which is essential to maintain the breasts in the desired position upon the body of the wearer. The auxiliary 15 straps in addition to the side and back bands will firmly secure the garment in position, the elastic straps being employed to make this firm mounting and yieldable mounting to compensate for body movement as well as chest expansion and contraction.

Garments of the type and kind under consideration are adaptable for use in all types and kinds of lowcut garments, and for use in conjunction with bathing suits and in what are termed sun-suits or bathing suits of this type and kind. The 25 brassière structure itself might constitute the garment or built into the fabric of a garment. When it constitutes a garment, the outer facing sheets will be made to match the other part of the suit.

Having fully described by invention, what I claim as new and desire to secure by Letters Patent is:

1. In garments of the class described, a pair of 35 substantially similar breast pockets, said pockets having wide adjacent and outer edge portions, means joining adjacent edge portions of the pockets, side and back bands attached to outer side edges of the pockets, means adjustably and 40 detachably coupling rear end portions of said bands, straps coupled with upper outer edge portions of each pocket and paralleling said bands, when arranged upon the body of the wearer, means on the straps and bands for detachably 45 and adjustably coupling the rear end portion of the straps with the rear end portion of the band of an opposed pocket, to aid in supporting the garment upon the body of the wearer, said 50 pockets being composed of inner and outer facings joined by spaced parallel stitchings arranged at lower and inner and outer side portions of the pockets, said stitchings forming between the facings curved channels, curved brace members 55 arranged in the channels of said pockets, and one of the facings having openings formed therein adjacent one end of the channels for detachable mounting of the brace members with respect to said pockets.

2. The combination with a body encircling 60 garment comprising breast pockets joined centrally of the front of the garment and body encircling bands for supporting the garment upon the body of the wearer, of supplemental garment supporting straps, said straps being attached to upper outer side edges of said pockets and adapted to be arranged around the body of the wearer substantially paralleling said bands, said straps being of sufficient length to be crossed at the back of the wearer, and means on said straps 65 and bands for detachably coupling the strap of one pocket with the band of an opposed pocket at the back portion of said band.

3. The combination with a body encircling 70 garment comprising breast pockets joined centrally of the front of the garment and body en-

circling bands for supporting the garment upon the body of the wearer, of supplemental garment supporting straps, said straps being attached to upper outer side edges of said pockets and adapted to be arranged around the body of the wearer substantially paralleling said bands, said straps being of sufficient length to be crossed at the back of the wearer, means on said straps and bands for detachably coupling the strap of one pocket with the band of an opposed pocket at the back portion of said band, and said last named means being adjustable.

4. The combination with a body encircling garment comprising breast pockets joined centrally of the front of the garment and body encircling bands for supporting the garment upon the body of the wearer, of supplemental garment supporting straps, said straps being attached to upper outer side edges of said pockets and adapted to be arranged around the body of the wearer substantially paralleling said bands, said straps being adapted to be crossed at the back of the wearer, means on said straps and bands for detachably coupling the strap of one pocket with the band of an opposed pocket at the back portion of said band, said bands having inner and outer facings, and said straps throughout the greater portion of their length being disposed between the inner and outer facings of said bands.

5. A shoulder strapless garment of the class described comprising a pair of pockets, means including body encircling bands for supporting the pockets upon the body of the wearer, means

reinforcing lower, side and part of the upper portions of each pocket for maintaining the garment and peripheral portions of the pockets firmly upon the body of the wearer around the major portion of the breasts in support of the breasts in the pockets of the garment, and in supporting the garment against displacement upon the body of the wearer, supplemental body encircling supporting straps attached to upper outer sides of each pocket, means on said straps and bands for coupling the straps to the bands of opposed pockets at the back portion of the garment, and the attachment of the straps to said bands being detachable and adjustable.
